UNITED STATES PATENT OFFICE

THOMAS F. MOONEY, OF MORRISTOWN, NEW JERSEY

FIREPLACE

Application filed February 12, 1929. Serial No. 339,450.

This invention relates to new and useful improvements in fireplaces, and aims to provide a device of this character that is composed of preformed slabs or tiles comprising the bottom, side and back walls of the fireplace to enable the workmen to rapidly set up the fireplace within the usual opening constructed in the wall during the erection of the building.

10 These preformed slabs or tiles are of a predetermined area, and will enable the workmen to construct a fireplace of a desired width, all of the slabs being of such an area and of such a construction as to enable the 15 side walls of the fireplace to be arranged parallel to each other or in converging relation towards their outer edges, and will also permit the end walls to be set up in predetermined spaced position.

20 In the drawings wherein like reference characters indicate corresponding parts throughout the several views:

Figure 1 is a perspective of a fireplace constructed in accordance with the present invention, a suitable facing for the fireplace being illustrated.

Figure 2 is a perspective of my improved fireplace.

Figure 3 is a front side elevation, the slabs or tiles being arranged so as to provide a relatively wide fireplace.

Figure 4 is a top plan view thereof.

Figure 5 is a fragmentary section taken substantially upon the line 5-5 of Figure 3, disclosing the joint between the side wall and back wall slabs when a relatively wide fireplace is constructed.

Figure 6 is a fragmentary vertical section taken substantially upon the line 6-6 of Figure 3 disclosing the joint between the adjacent longitudinal edges of the back wall slabs or sections.

Figure 7 is a front side elevation of the fireplace when the slabs or sections are arranged to provide a narrow fireplace.

Figure 8 is a top plan view thereof.

Figure 9 is a fragmentary horizontal section, taken substantially upon the line 9-9 of Figure 7, and disclosing the joint between the side wall slabs and the back wall slabs

when said slabs are arranged in narrow fireplace forming position, and

Figure 10 is a fragmentary horizontal section disclosing the joint between the side wall slabs and the back wall slabs when the side 55 wall slabs are arranged in directly outwardly projecting parallel position.

Now having particular reference to the drawings, my novel fireplace consists of a flooring or base 5 composed of slabs or tiles 60 of any suitable material, such as fire clay or the like. The base 5 is so formed as to provide at the rear edge of the floor and intermediate the ends thereof an ash opening 6. The fireplace further consists of side wall 65 slabs 7-7 of predetermined height and width, the vertical rear edges of these slabs being tapered from their upper ends to a point below their centers to provide inclined rear edges 8-8. The rear edges of these side wall 70 slabs 7-7 are formed throughout their entire length with wide V-shaped mortar receiving channels 9, see Figures 5, 6, 9 and 10. The back wall of the fireplace consists of a narrow lower slab 10, and a wide upper slab 11, the width of the lower tile being equivalent to the length of the untapered portions of the rear edges of the side wall slabs 7-7, and the width of the upper section 11 being equivalent to the length of the tapered edges 75 8-8 of said side wall slabs. The lower edge 80 of the upper back wall slab 11 is bevelled at opposite sides of its center line to provide inclined faces 11'-11' at the lower edge thereof, and to enable the lower edge of the upper section to be secured flush by a mortar joint to the lower section, regardless of which faces of the back wall sections are exposed to the interior of the fireplace, see Figures 3 85 and 7.

The end edges of the back wall tiles or slabs 10 and 11 are bevelled as at 10^a and 11^a for a purpose presently to be described.

When it is desired to construct a relatively wide fireplace, the rear wall sections 10 and 11 are arranged as illustrated in Figures 2, 3, 4 and 5, that is, the bevelled edges are exposed to the back of the fireplace, and the side wall slabs 7-7 are arranged in outwardly converging manner, as more clearly dis- 95 100

closed in Figure 5, and the extreme edges of the back wall slabs 10 and 11 project into the channels 9 of the side wall slabs, and are secured therein by mortar or the like, as illustrated. Also, the adjacent edges of the back wall slabs 10 and 11 are secured by a mortar joint as indicated in Figure 6, and by reason of the tapered portions of the rear edges of the side wall slabs, the upper section 11 of the rear wall slab will rest upon an incline as is usually desired. If preferred to have the side wall slabs in directly outwardly projecting parallel position, and at the same time to provide a relatively wide fireplace, it is only necessary to arrange the inner edges of the side wall slabs directly against the inner faces of the back wall slabs at the extreme ends thereof, and to secure the side wall slabs to the back wall slabs by placing mortar within the channels of the side wall slabs.

Whenever it is required to have a slightly narrower fireplace, the back wall slabs are reversed to the position illustrated in Figures 7, 8 and 9, that is, the tapered ends thereof are exposed to the interior of the fireplace, as in Figure 9. The inner ends of the bevels are arranged within the channels of the side wall slabs if it is desired to have these slabs extend in converging relation, but if a still narrower fireplace is necessary, or it is desired to dispose the side walls in parallel position, the side wall slabs are arranged at the direct ends of the inner surfaces of the back wall slabs as illustrated in Figure 10, and are secured to the back wall slabs by a suitable mortar joint as illustrated.

In view of the foregoing description when considered in conjunction with the accompanying drawings, it will be apparent that I have provided a novel and simple sectional fireplace, that may be readily set up by unskilled workmen, and even though I have herein shown and described the fireplace as consisting of a particular number of slabs, it is obvious that the various walls of the fireplace may comprise an additional number of slabs. Also, the faces of the slabs may be of any desired design, and said slabs may be of any predetermined area, as well as being made up of any suitable material, and this without affecting the spirit and scope of the appended claims.

Having thus described my invention, what I claim as new, and desire to secure by Letters Patent, is:

1. In a sectional fireplace of the character described, a base or floor unit, a pair of side wall units, a back wall unit, said side wall units having inclined rear edge portions extending from a point adjacent their lower ends to their upper ends, said back wall unit consisting of sections adapted to span the side wall units one of which is adapted for engagement at its opposite ends with the un-inclined rear edges of the side walls and the

outer one of which is adapted for engagement with said inclined edges of the side walls to provide a partially inclined rear wall, the opposite ends of the rear wall sections being bevelled, the inner edges of said side walls being provided with channels of obtuse cross section for receiving the ends of the bevels of said rear wall sections.

2. A sectional fireplace of the character described comprising side wall units, and back wall units, having connected edge portions, and co-acting means on said edge portions for connecting the side and back wall units together in reverse and laterally shifted positions respectively.

3. In a sectional fireplace of the character described, a base or floor unit, a pair of side wall units, a back wall unit, said side wall units having inclined rear edge portions extending from a point adjacent the lower ends to their upper ends, said back wall unit consisting of sections adapted to span the side wall units, one of which sections is adapted for engagement at its opposite ends with the uninclined rear edges of the side wall units, and the other of which sections is adapted for engagement with said inclined rear edge portions of the side wall units to provide a partially inclined rear wall, the adjacent meeting ends of the back and side wall units having interfitting means whereby the same may be secured together in reverse and laterally shifted positions respectively.

In testimony whereof I affix my signature.

THOMAS E. MOONEY.
